UNITED STATES PATENT OFFICE.

ARCHIBALD WILLIAM BLAIR, OF WELLINGTON, NEW ZEALAND.

SPANNER OR WRENCH.

1,359,660.

Specification of Letters Patent. Patented Nov. 23, 1920.

Application filed December 3, 1919. Serial No. 342,210.

To all whom it may concern:

Be it known that I, ARCHIBALD WILLIAM BLAIR, subject of the King of Great Britain, residing at Wellington, in the Dominion of New Zealand, have invented new and useful Improvements in Spanners or Wrenches; and I do hereby declare the following to be a full, clear, and exact description of the same.

10 This invention relates to shifting or adjustable spanners or wrenches and it has been devised with the object of providing a construction by means of which the spanner is made automatically adjustable to any of 15 the sizes within its range and by which also a "ratchet" action is obtainable in the use of the spanner, that is to say, the spanner will slip idly around the nut when moved backward from its work and will lock there- 20 with when moved up to its work.

The invention consists broadly in the construction of the spanner with a head pivotally attached to a handle so that they may move in relation to one another in the plane 25 of the head, and with such head formed with a fixed block shaped to engage either one or two sides of a nut and having a pair of jaws mounted therein, one on each side of such fixed block and which jaws are so shaped as 30 to extend outward on each side of the block and so mounted and controlled that the turning movement of the handle relatively to the head in one direction will move such jaws out from the block while the reverse 35 movement will move them in to engage the said block. These jaws are adapted to engage the two opposite sides of the nut re- 40 spectively adjacent to the side or sides en- gaged by the fixed block, and thus to hold the nut between them.

A spring controls the moving parts of the spanner so as to turn the handle in a plane approximately straight with the head and to draw the jaws inward against the 45 block so as to form the minimum size. The jaws open against the action of this spring and thereby allow of the spanner being forced sidewise onto a nut and for the jaws accommodating themselves to close in onto 50 such nut and engage the faces thereof.

The invention will however, be more fully described in relation to the accompanying sheet of drawings, in which:—

Figure 1 is a side elevation of the spanner.

Fig. 2 is a side elevation thereof with one 55 of the cover plates of the head removed.

Fig. 3 is a back edge elevation thereof.

Fig. 4 a detail view showing the relative arrangement of the two jaws.

In the construction shown, a spanner specially adaptable for use upon hexagonal nuts is shown, but such spanner is however capable of use upon square nuts of a size within its range, although if desired, the principle of construction embodied may be readily adapted to render the spanner specially applicable for use on square nuts. In this description of the invention therefore, the construction applicable to hexagonal nuts is particularly set out.

According hereto, the spanner handle A is pivoted at a between a pair of cover plates B forming the head and secured together with suitably positioned distance blocks B' between them, by approved means such as 75 the screw pins b. The handle and head are thus capable of swinging in relation to one another in a plane corresponding to the movements of the spanner, but a helical spring C interposed between a bell crank 80 lever extension D of the handle and the bottom of one of the blocks B' serves to keep the two in a normal condition such that they turn outward from one another to assume approximately a continuous plane.

E is a block fixed between the cover plates B at the top of the head. The upper edge of this block is shaped, as shown in Fig. 2, to form two faces inclining inward from both side edges at such an angle as to form 90 an angle of 120° where they join, and thus adapt the block to fit onto one corner of a hexagonal nut and for its faces to engage the faces of the nut adjacent to such corner. The cover plates B also have their upper edges 95 shaped to coincide with the block. The block sides are made parallel for a distance and then converge inward to the center line so as to form faces on the underside extending outward and upward at an angle of 60° 100

to one another. The blocks B' are arranged one on each side of the central block E and each one of these is formed with an angular inner face extending upward and outward 5 in a line parallel with the undersurface of the block E on the corresponding side. An angular space is thus formed between the central block and the block B' on each side and inclosed between the cover plates B, and 10 this space forms a guide to receive one of the jaws of the implement.

These jaws F and G are made to fit neatly 15 in between the cover plates B and each is shaped so that its inner portion lies within one of the spaces between the central block E and the block B' on one side, while its outer end projects upward at an angle thereto and with its inner face parallel with the corresponding side face of the central 20 block E. The two jaws have their inner faces thus extending in parallel lines to each other and projecting outward from the opposite sides of the block E. Each face therefore forms with the adjacent angular 25 face of the block top, an angle of 120° so that the two jaws will lie neatly against the respective faces of the nut engaged by the block E. The arrangement of the guides formed by the block E and the blocks B' at 30 a diverging angle of 60°, thus provides that when the jaws F and G are moved along such guide, the outer portions or ends of the jaws will maintain the same relative angles to the faces of the block E and to 35 one another, while they will be moved farther apart, thus adapting them to fit on different sizes of nuts. Their inward movement is restricted by their engagement with the side faces of the block E as shown in 40 the drawing, and in this position the spanner is at its minimum size. The maximum size is governed by the length of the jaws and the amount of movement permitted the jaws outward along their respective guides.

45 To control the jaws and keep them normally drawn inward, their inner ends are connected to the bell crank lever extension D of the handle by means of the two links H—H' one of which is pivoted to one of the jaws and the other to the other jaw, while both have their lower ends pivoted in 50 the end of the extension D. Consequently the turning movement of the handle on its pivot a will, as it is turned in against the spring C, force the jaws upward and outward, while the outward turning thereof will draw the jaws downward and inward. The handle in its normal state is adjusted to draw the jaws back to the minimum position 55 and the engagement of the jaws, when in this position, with the block E will keep the handle rigid with the head when strained in the opposite direction. Likewise, when the jaws are moved out from

their minimum position, and fitted onto a 65 nut, the strain on the handle exerted by the spring will keep the jaws in close engagement with such nut and the straining of the handle in the closing direction will lock the spanner onto the nut in order that 70 the working strain may be placed on the spanner to turn the nut. The opening of the jaws upward and outward on the backward turning of the handle A permits the corners of the nut to be passed over to obtain 75 a fresh grip and the action of the spring on the release of the handle causes the jaws to close in onto the nut faces ready for a further working strain. In this way the spanner is ratchet acting.

80 The end of the jaw G when pressed onto a nut sidewise will open out both jaws against the action of the spring so that the spanner will automatically adjust itself to the required size.

85 The construction of the jaws in this manner will allow for either hexagonal or square nuts being gripped within them and upon the top of the block E, in the case of a hexagonal nut, the nut thus being engaged on four of its faces, and in the case of a square nut, on three of its faces. If desired, the outer end of one jaw may be formed with the inward extension G' having its inside face at an angle of 120° to the 90 inside face of the jaw so as to permit of a hexagonal nut being engaged on five of its faces. If both jaws have a similar extension six sides of a hexagonal may be engaged. The same principle of construction 95 can be adopted if desired for use only on square nuts, but in such case the block E will be constructed with a flat top and the guides for the jaws will be at different angles to that used in the illustration.

100 The implement may also be adapted for use as a pipe wrench by forming the jaws with gripping teeth on their inner faces.

I claim:—

1. In spanners or wrenches a head and handle pivotally connected to turn one upon the other in the plane of the head, such head being formed with a centrally fixed block and having a pair of jaws mounted therein, one on each side of said block and each shaped to project outwardly beyond the outer face of the block, connections between the handle and the jaws whereby the relative movement of the handle to the head, in one direction, will move the jaws away from the respective sides of the fixed block, and the movement of the handle in the other direction, will draw the jaws in to the block, and a spring normally turning the handle in the latter direction, substantially for the 12 purposes specified.

2. In spanners or wrenches, a head formed with a fixed central block, guides formed one

- on each side of such block and diverging outwardly from one another, a pair of jaws fitted one in each of said guides and shaped so that their outer ends project outwardly 5 beyond the outer face of the fixed block, a handle pivoted to the head so as to be capable of turning in the plane of the head, connections between the handle and the said jaws whereby the turning movement in one direction will force the jaws outward in their 10 respective guides and movement in the reverse direction will draw them inward therein and a spring normally turning the handle in the latter direction, substantially for the purpose specified.
3. In spanners or wrenches, a head formed with a fixed central block, guides formed one 20 on each side of said block and diverging outwardly from one another, a pair of jaws fitted one in each of said guides and shaped so that their outer ends project outward beyond the outer face of the fixed block, a handle pivoted to the head so as to be capable of turning in the plane of the head, a bell 25 crank lever extension upon such handle, links
- extending between the end of such extension and the respective jaws, and a compression spring bearing between the head and said extension, and normally pressing the handle outward on its pivot, substantially as specified. 30
4. In spanners or wrenches, the combination with a head comprising a fixed central block and a pair of jaws mounted in said block one on each side thereof and projecting out beyond its surface, of a handle pivoted in the head to turn in the plane of the head and connections between the jaws and said handle whereby turning movement in one direction moves the jaws outward from 40 the block and turning movement in the other direction draws them downward and inward on to the block, substantially as specified.

In testimony whereof I have signed this specification in the presence of two subscribing witnesses.

ARCHIBALD WILLIAM BLAIR.
